SANDING WHEEL

Ernest Dunford, St. Louis, Mo., assignor to Landis
Machine Company, St. Louis, Mo., a corpora-
tion of Missouri

Application March 11, 1936, Serial No. 68,202

8 Claims. (Cl. 51—194)

The invention relates to sanding wheels of the type commonly used on shoe finishers, and consists in novel construction of the body of the wheel and the means for mounting the same on a shaft.

Wheels of the type referred to are usually made in two segments hinged to each other to swing transversely of the shaft to permit application and removal of a strip of sandpaper to their outer peripheral surfaces. The main object of the present invention is to facilitate the securing and releasing of such wheel sections in and from their operating relation to each other on the shaft upon which they are mounted.

Another object of the invention is to eliminate eccentricity and play in the assembled device which frequently arises in the ordinary wheel from the loosening of the screws securing the wooden wheel segments to the elements which mount them on the shaft.

Another object of the invention is to protect the elements, which secure the wheel segments together, from dirt, sand, and other debris.

These and other detail objects which will be apparent from the following description may be obtained from the structure shown in the accompanying drawing, in which—

Figure 1 is, in part, an elevation and, in part, a section through a sanding wheel and the means for mounting it on the shaft which is also illustrated, the parts being shown in released position.

Figure 2 is, in part, a side elevation and, in part, a vertical section taken on the line 2—2 of Figure 1.

Figure 3 is a section and view corresponding to Figure 1 but showing the parts in an operating position.

The body of the wheel comprises two wooden segments 1 and 2 hinged to each other at 3 and covered by a layer 4 of felt or similar cushioning material over which a strip 5 of sandpaper or emery cloth is applied, the ends 6 of the strip being turned inwardly and gripped between the abutting edges of segments 1 and 2. The above described construction is that usually found in wheels of this type.

On the annular faces of segments 1 and 2 are bosses 7 which, when the segments are moved towards each other, form frustro-conical projections extending in opposite directions from the wheel.

Mounted upon the power shaft 8 is a fixed collar 9 secured in place on the shaft by set screws 10 and including a flange 11 having a frustro-conical recess 12 disposed to receive the corre-

sponding frustro-conical projection 7 on the wheel. Collar 9 includes a sleeve 13 extending through the wheel.

A movable collar 14 includes a sleeve 15 receiving sleeve 13 on collar 9 and slideable along the same. A flange 16 on collar 14 has a frustro-conical recess 17 corresponding to recess 12 and collar 9 and disposed to receive the corresponding projection 7 on the wheel body.

Obviously movement of collar 14 towards collar 9 results in clamping the wheel segments between the collars, the interengaging faces of projection 7 and recesses 12 and 17 serving to center the segments and to force them tightly against each other.

Means for effecting such movement of the collars is provided by a cam slot 18 in sleeve 15 and a corresponding stud 19 threaded into sleeve 13. Arrow A (Figure 3) indicates the normal direction of rotation of the shaft whereby collar 9 and stud 19 are rotated to thrust collar 14 towards collar 9. A pin 20 on collar 14 projects into a recess therefor in segment 2 and positively rotates the wheel irrespective of the frictional grip on the wheel by the opposed collars.

When the sandpaper is to be changed, or the wheel opened up for any other reason, the same may be rotated in the opposite direction thereby rotating collar 18 relative to collar 9 and releasing the grip on the wheel.

When the wheel is released and the split portion is opposite stud 19, the latter may be removed from collar 9 with a screwdriver and the two collars completely disassembled from each other and the wheel removed from the device for replacement or reversal.

When the parts are assembled as shown in Figure 3, the cam slot and pin constituting the operating parts of the mechanism are located in a tight chamber formed by the annular opening 40 21 through the wheel body and by the adjacent portions of the collars.

The device is simple, economical, and effective for the intended purpose as stated in the objects of the invention set forth in the introductory portion of the specification. Obviously details of the structure may be varied without departing from the spirit of the invention and the exclusive use of all modifications as come within the scope of the claims is contemplated.

I claim:

1. In a device of the class described, segments movable towards each other to form a sanding wheel, segment clamping collars at opposite annular faces of said segments and having over-

50

55

lapping sleeves slidable axially over each other, a radial stud on one of said sleeves, the other of said sleeves having a stud-receiving slot inclined longitudinally of the length of the sleeve to cam 5 said collars towards each other when they are rotated relatively.

2. In a device of the class described, segments movable towards each other to form a sanding wheel with an opening extending axially there- 10 through, collars engaging the annular faces of said wheel respectively and provided with sleeves extending inwardly of said opening, said sleeves telescoping with each other and having corresponding interior peripheries for fitting over a power shaft, a radial stud on the inner of said sleeves, there being a slot through the other of said sleeves inclined circumferentially and longitudinally thereof and receiving said stud whereby 15 relative rotation of said collars causes said pin 20 and slot to cam said collars towards each other to grip said segments between them.

3. A structure as described in claim 2 in which the annular faces of said wheel include frustro-conical bosses and the opposing faces of said 25 collars include correspondingly shaped recesses for receiving said bosses and drawing said segments more tightly together radially of the device as said collars are cammed towards each other.

4. In combination, an operating shaft, spaced 30 collars each fitting on said shaft intermediate its ends, segments between said collars movable towards each other to form a sanding wheel with an axial opening receiving said shaft and closed at its ends around said shaft by said collars, and 35 means in the closed space between said collars and between said shaft and the periphery of said opening for drawing said collars towards each other when rotated relatively, there being a connection between one of said wheel segments and 40 one of said collars for positively rotating the latter by rotation of said segment about said shaft.

5. In combination, an operating shaft, a collar having a cylindrical sleeve fitting over said shaft and having a flange extending radially from said 45 sleeve, another collar having a cylindrical sleeve slidably fitting over said first-mentioned sleeve and having a flange extending radially of its sleeve, segments between said flanges movable towards each other to form a sanding wheel with 50 an axial opening receiving said sleeves and closed at its ends around said sleeves by said flanges, a cam stud on one of said sleeves and a cam slot

on the other of said sleeves for drawing said collars together when rotated relatively, said cam element being closed off from dirt due to operation of the wheel by said shaft, collar flanges and the inner periphery of said wheel axial opening, there being a connection between one of said wheel segments and one of said collars for positively rotating the latter by rotation of said segment about said shaft.

6. In a sanding wheel unit arranged for application to a through shaft, a pair of sleeves each slidable over the shaft and arranged for telescoping engagement with each other independently of their relatively axial rotation, means on said sleeves functioning independently of the shaft to which they are applied for moving the sleeves axially of each other when they are rotated relative to each other, there being radially extending collars on said sleeves, and sanding wheel forming segments mounted on the outer of 20 said sleeves and arranged to be gripped between said collars when said sleeves are moved towards each other.

7. In a sanding wheel unit arranged for application to a through shaft, a pair of sleeves 25 each slidable over the shaft and arranged for telescoping engagement with each other independently of their relatively axial rotation, one of said sleeves having a slot inclined longitudinally there- 30 of and the other of said sleeves having a pin projecting into said slot whereby said sleeves may be moved axially of each other when they are rotated relative to each other and independently of the rotation of the shaft, there being radially extending collars on said sleeves, and sanding 35 wheel forming segments mounted on the outer of said sleeves and arranged to be gripped between said collars when said sleeves are moved towards each other.

8. In combination, a shaft, an annular sleeve- 40 like member slidably receiving said shaft and including a radially extending collar, another annular element slidably receiving said shaft and including a radially extending collar and a cylindrical part slidably receiving said member, said 45 collars having opposing faces, a segmental sanding wheel surrounding said part and arranged to be gripped between said collar faces, and means on said member and part for moving them axially when they are rotated relative to each other.

ERNEST DUNFORD.
